UNITED STATES PATENT OFFICE.

JAMES B. ANDERSON, OF PITTSBURGH, PENNSYLVANIA, ASSIGNOR TO PUMPLESS BLOW TORCH COMPANY, OF PITTSBURGH, PENNSYLVANIA.

BLOWTORCH.

Application filed September 28, 1921. Serial No. 503,838.

To all whom it may concern:

Be it known that I, JAMES B. ANDERSON, a citizen of the United States, residing at Pittsburgh, in the county of Allegheny and 5 State of Pennsylvania, have invented certain new and useful Improvements in Blow-torches, of which the following is a specification.

This invention relates to blow-torches and 10 more especially to torches adapted for the use of liquefied gas as fuel.

One of the main objects of the invention is to provide a torch in which fuel in either gaseous or liquid form may be used, as desired. A further object is to provide a torch in which the possibility of the clogging of the burners has been reduced to a minimum, if not entirely eliminated. Still 15 another object is to provide a torch having simple and efficient means to regulate the feed of the fuel in either liquid or gaseous state. A further object is to provide a torch of simple design and construction and which can be manufactured at low cost. 20 Further objects and advantages will also appear from the specification and drawings which form a part of this application.

The present application is to cover improvements over the construction indicated 30 in Patent No. 1,364,972, June 11, 1921, and the Patents Nos. 1,390,264 and 1,390,265 issued on September 13, 1921, to Charles H. Allen and myself.

Referring to the drawings:

Fig. 1 is a central vertical sectional view 35 through a torch constructed in accordance with my invention.

Fig. 2 is a rear elevation of the standard and associated parts, with the extreme parts 40 broken off.

Fig. 3 is an enlarged fragmental sectional view through a burner used in my torch.

Fig. 4 is an end view corresponding to 45 Fig. 3.

Fig. 5 is an enlarged sectional view through the casing of the filling valve used in connection with the present invention.

Fig. 6 is a top plan view of Figure 5.

Fig. 7 is a side elevation, partly in section, showing the filling valve.

Fig. 8 is a top plan view of Figure 7.

Fig. 9 is an enlarged side elevation of a fuel strainer used in my torch.

Fig. 10 is a top plan view of Figure 9.

Referring to Figures 1 and 2, the tank 1, made of steel, copper or any other suitable material, is provided with an opening at the center of its top into which the centrally threaded collar 2 is secured in any suitable leak-proof manner. A standard 3, terminating at its lower end with the threaded shank 4 is secured in said collar. In the shank of said standard are drilled to the required depth four ducts; ducts 5 and 6 leading respectively to a test valve 7 and a safety valve 8; the ducts 9 and 10 being respectively the liquid fuel and gaseous fuel ducts, which are governed by their corresponding valves 11 and 12. The ducts 9 and 10 can be put in communication with the main fuel duct 13, drilled in the upper part of the standard, by the short connecting ducts 14 and 15 and through the proper manipulation of the valves 11 and 12. In 70 the liquid fuel duct 9 is secured a bent tube 16 reaching close to the bottom of the tank and having at its lower end a strainer 17 made of fine wire mesh to prevent the entrance within the liquid fuel duct of any foreign matter which might be present in the fuel. The tank is provided with the concave bottom 18 at the center of which is securely mounted or brazed the collar 19 which is centrally threaded to receive the hollow 85 valve casing 20, an enlarged view which is shown in Figure 5. This casing consists of a polygonal flange 21, on both sides of which are the threaded shanks 22 and 23. The upper shank 22 engages the collar 19 and is provided with the sleeve extension 24 properly finished interiorly to act as a cage for the cylindrical filling valve 25, in the bottom of which is inserted a disc 26 of any suitable and preferred soft metal 90 to insure a leak-proof contact with the seat 27 provided in the casing. The movement of the filling valve 25 is limited and guided against rotation within the sleeve 24 by a pin 28, conveniently secured in the sleeve 24 and engaging a slot 29 cut in the valve. Adjacent the bottom of the sleeve 24 I provide therein the apertures 30 to allow the passage of the liquid when filling the tank. The casing is closed at the bottom by means of a threaded wing cap 31; it being noted that the depression in the concave bottom 18 is such that the wing cap will not extend beyond the lower edge of the tank. 105 110

The test valve 7 is used to indicate the presence of fuel in the tank. The shank of this valve is threaded and terminates with a point which engages the suitably formed aperture 32, which is outwardly enlarged to provide a passage for the fuel and allow its escape through the small holes 33, when the valve is opened. A tube 34, the lower end of which is bent upward as indicated 10 in Figure 1, is secured within duct 5. The object of this bend is to prevent the jet of fuel, occurring during the filling of the tank (which is then held in upright position) from forcing the liquid fuel directly 15 into the test valve, and to prevent the clogging of the latter by any foreign matter which might be present in the fuel.

The safety valve 8 is in direct connection with the duct 6 and is composed of cap 35 having an enlarged bore 36 extending partially therethrough and terminating with the lateral apertures 37. A thin disc or diaphragm 38 is inserted between the cap and the end of the nipple 39; the thickness 25 of said diaphragm being calibrated to secure the tearing thereof when a certain pressure within the tank is exceeded.

My blow-torch is provided with a main burner 40 and the pilot burner 41 which are 30 severally supplied with fuel by the main duct 13. Each of said burners is composed of the interiorly threaded cap 42 provided with a central aperture 43. A diaphragm 44 made of very thin metal is clamped by the cap 35 against the face of the nipples 40^a and 41^a and is provided at the center with a small aperture 45 for the passage of the fuel. The deposit of matter in this aperture will be 40 greatly hindered, if not totally impossibilitated, owing to the thinness of the diaphragm and the vibrations occurring therein due to the passage of the fuel therethrough. The pilot burner 41 is regulated by means of a valve 46 securely mounted in the extension 45 47 provided on the standard. This valve is composed of a stem 48 terminating with the pointed end 49 engaging the short duct 50; this stem is provided intermediate its ends with the threaded portions 51 and the collar 50 52 slidingly fitting within the counter-bored aperture 53. The spindle is threaded into the valve casing 54, the outer end of which is counter-bored to provide room for the valve packing 55 and the valve gland 56. The packing is compressed by 55 means of the interiorly threaded cap 57 engaging corresponding threads provided on the casing. The valve stem is also fitted with a handle 58 which is securely mounted thereon after the stem has been inserted through its casing.

The main burner 40 is without individual valve and the flow of fuel therethrough is regulated either by valve 11 or 12 according 60 to whether the burner is operated with liquid

or gaseous fuel. The main duct 13 is plugged at its upper end by the screw 59 acting upon a sealing plug 60, generally made of lead.

The passage of the fuel from the tank to the main burner will remain uninterrupted whether or not the valve of the pilot burner be closed, owing to the enlarged aperture 53 surrounding the valve stem adjacent the point thereof.

The pilot burner is enclosed by a casing 61 depending from the perforated flame tube 62 and communicating therewith through the aperture 63, generally provided with a wire mesh screen 64 to prevent the entrance 80 of foreign matter within the casing 61. In the present construction the flame tube and the casing are made integral and the casing is suitably turned to engage a corresponding bead 65^a turned upon the extension 65 85 formed upon the standard. Suitable screws (not shown in the drawing) are provided to securely hold flame tube and casing to the standard.

The torch is supplied, as usual, with a handle 66 which is secured to the tank in any suitable manner, such as by means of the straps 67 and 68 surrounding the tank and securely clamped thereon by means of the screws 69. The principal parts of my torch having been described, the operation thereof will be readily understood and is as follows:

To fill the blow torch with fuel, the wing-cap 31 is removed and the torch is connected, while in upright position, with a storage tank containing the fuel. The pressure created by the fuel, will then lift the filling-valve 25 and the fuel will enter the tank through the lateral apertures 30 provided in the valve-cage. The supply of fuel is discontinued after the liquid has reached a level slightly below the bent tube 34. This is ascertained by opening the test valve and observing the state of the fuel escaping therethrough. An escape of liquid fuel will indicate that the latter has reached too high a level in the torch-tank, whereas a gaseous escape is indicative of the fact that the fuel is still below the level of the bent tube.

To operate the torch with liquid fuel, for instance, the pilot valve 46 and the valve 11 are opened; the pressure in the storage tank will then force the properly strained fuel through the tube 16, the duct 14 and then to the pilot burner 41 and the main burner 40. The fuel flowing through the main burner is now ignited by applying a lighted match, for instance, near the perforations 62^a or 62^b, provided in the flame tube, and the flame is transmitted to the pilot burner, through the hole 63.

As already stated, the main burner may be operated when the pilot burner is shut off; but it is not possible in this torch to operate the pilot burner singly. The principal ob-

jects of the latter are to insure a perfect vaporization of the fuel issuing from the main burner and to prevent the extinction of the flame thereof in windy places. This latter result is due to the protection afforded the pilot flame within the enclosed casing 61.

The operation of the torch with gaseous fuel is effected identically as described for liquid fuel; the only difference being that the gaseous fuel valve 12 is opened instead of the valve 11.

It will be understood, of course, that the arrangement I have herein shown is merely suggestive of many that might be adopted in

carrying out my invention, and I do not wish to be limited to the construction illustrated, otherwise than as specified in the appended claim.

What I claim is:

In a torch, the combination of a plurality of burners of the character described; a test-valve; a tube connecting said test-valve with the tank of said torch; an upward bend provided at the lower end of said tube, and a filling-valve positioned centrally of the bottom of said torch.

In testimony whereof I affix my signature.

JAMES B. ANDERSON.
